UNITED STATES PATENT OFFICE.

WILLIAM H. TIVY AND LEO EHRLICH, OF ST. LOUIS, MISSOURI, ASSIGNORS
TO THE AMERICAN ROLL PAPER COMPANY, OF SAME PLACE.

PAPER-CUTTER.

SPECIFICATION forming part of Letters Patent No. 392,895, dated November 13, 1888.

Application filed February 13, 1888. Serial No. 263,792. (No model.)

To all whom it may concern:

Be it known that we, WILLIAM H. TIVY and LEO EHRLICH, both of the city of St. Louis, in the State of Missouri, have invented a certain new and useful Improvement in Paper-Cutters, of which the following is a full, clear, and exact description, reference being had to the accompanying drawings, forming part of this specification, and in which—

10 Figure I is an elevation of our improved cutter. Fig. II is an end view. Fig. III is a detail section taken on line III III, Fig. I. Fig. IV is a detail top view.

Our invention relates to an improvement in machines for holding and cutting wrapping-paper; and our invention consists in features of novelty hereinafter fully described, and pointed out in the claims.

Referring to the drawings, 1 represents a base, to which ends 2 are secured. These ends have extensions 3, upon which the gudgeons 5 of the paper-roller 4 bear and move.

6 represents arms pivoted at 7 to the ends 2, and which bear against the extended ends 3 of the gudgeons 5, and, being inclined on their lower edges, tend to move the paper-roller forward as the paper 9 is removed. In these parts *per se* we claim no invention in this application.

8 represents the knife secured to the outer ends of the arms 6 and extending upwardly and outwardly from the roll of paper. Journaled in the arms a short distance from the knife, and between it and the roll of paper, is a roller, 9^a. The edge 11 of the paper is passed upwardly between the roller 9^a and the knife, and when it is desired to remove a portion of it it is pulled out and moved over against the edge of the knife and cut off. The portion 11 then between the roller and the

knife will spring back to the vertical position 40 shown in Fig. II, forming an easy finger-hold when more paper is wanted.

The extensions 3 have bars 15 to prevent the displacement of the paper-roller.

We prefer to make the roller 9 removable, 45 so that it may be taken out, if desired, in placing the paper between it and the knife. We have shown it removable by forming grooves in the upper faces of the arms to receive the journals or gudgeons of the roller.

We claim as our invention—

1. In a paper-cutter, in combination with a paper-roller, the paper-roller support, an upwardly-extending knife, a roll of paper on which the knife is supported, having an upwardly-extending free end in rear of the knife, and a guide-roller located in the gap between the free end and the roll, substantially as described.

2. In a paper-cutter, in combination with a paper-roller, the support, an upwardly-extending knife, a roll of paper on which the knife is supported, having an upwardly-extending free end in rear of the knife, and a removable guide-roller located in the gap between the free end 65 and the roll, substantially as described.

3. In a paper-cutter, the combination of the roller upon which the paper is wound, a support for the roller, arms pivoted to the support, knife on the arms, and roller journaled 70 in the arms a distance from the knife, and between which and the knife the paper passes, substantially as and for the purpose set forth.

WILLIAM H. TIVY.
LEO EHRLICH.

In presence of—

EDWD. S. KNIGHT,
JOS. WAHLE.
